(57) **CLAIM**

The ornamental design for a decorative support for a street sign, as shown and described.

DESCRIPTION

FIG. 1 is a front elevational view of the decorative support for a street sign, the rear side being a mirror image;

FIG. 2 is a side elevational view taken from the right side of FIG. 1;

FIG. 3 is a top plan view of FIG. 1; and,

FIG. 4 is a bottom plan view of FIG. 1.

The broken lines showing in FIG. 1, FIG. 2, FIG. 3 and FIG. 4 are for environmental purposes only and form no part of the claimed design.
